UNITED STATES PATENT OFFICE.

EDWARD WIDEEN, OF VANCOUVER, BRITISH COLUMBIA, CANADA.

CLOTHES-DRIER.

1,276,300.

Specification of Letters Patent. Patented Aug. 20, 1918.

Application filed March 1, 1918. Serial No. 219,819.

To all whom it may concern:

Be it known that I, EDWARD WIDEEN, a subject of the King of Great Britain, and a resident of the city of Vancouver, in the Province of British Columbia, Canada, have invented certain new and useful Improvements in Clothes-Driers, of which the following is a specification.

My invention relates to improvements in clothes driers, and the object of my invention is to provide a simple and useful means for supporting clothes to be dried and which, while being compact and of great convenience in places of limited accommodation, such as apartment houses, provides a maximum clothes drying capacity.

I attain this object by the construction illustrated in the accompanying drawings in which

20 Figure 1 is a side elevation of my device closed.

Fig. 2 is a plan view.

Fig. 3 is an enlarged sectional plan view taken on the line *a—b* of Fig. 2.

25 Fig. 4 is a side elevation of the device extended.

Fig. 5 is a detail view of a group of drying rods.

Similar figures of reference indicate similar parts throughout the several views.

My device consists preferably of three tubular sections 1, 2 and 3, telescopic one within the other, and of such length that when extended its upper end is within easy

35 reach of the user.

The lower section 1 is provided with a suitable weighted base 4 and with an inner tubular section 5 spaced from the outer section 1, this inner section 5 depending from the outer section head end covering plate or closure 6 and forming a tubular guide in which the intermediate section 2 is vertically slid able, the upper end of the section 5 being extended above the covering plate 6 and compressed by means of a divided band 7 passed therearound and adapted to be drawn together at its ends by a thumb screw 8 so that the section 2 may be held against vertical movement in any position to which it may be raised or lowered. The space between the wall of section 1 and the wall of section 5 is divided into four compartments by vertical partitions 9.

50 The intermediate section 2 which is, as stated, vertically slid able in the tubular guide 5, is also provided with an inner sec-

tion 10 spaced from the inner wall of the outer section 2 and depending from its head end covering plate 11 to form a tubular guide for the upper section 3, the upper end 60 of the guide being extended above the plate 11 and compressible to hold the section 3 in any adjusted position by means of a divided band 12 and thumb-screw 13, as already described with reference to band 7 65 and screw 8. The space between the wall of section 2 and the wall of section 10 is divided into three compartments by means of vertical partitions 14.

The upper section 3 is closed at its upper 70 end by a plate 15 from which extends downwardly a partition 16 dividing the interior of the section into two compartments.

17 indicates the clothes-supporting rods which are arranged in groups and disposed 75 to hang normally vertical within their respective compartments, that is, there is one group of five rods in each of the four compartments of the lower section 1, or twenty rods in all in the lower section; one group 80 of five rods in each of the three compartments of the intermediate section 2, or fifteen rods in all in the intermediate section; and one group of three rods in each of the two compartments of the upper section 3, or 85 six rods in all in that section. The number of rods employed throughout may, however, be varied. Each rod is eyed at its lower end, and they are loosely connected, in groups as just described, by staple like 90 members 18, to plates 19, as shown in Fig. 5, these plates being curved to conform to the contour of their respective compartments and fitting loosely in the same so that they may be freely movable vertically therein, as shown in Fig. 3. The covering or closure plates 6, 11, and 15 are provided with suitable slots through which the rods 17 extend, and the upper ends of rods of the lower and intermediate sections are provided with knobs 20 while the upper ends of the upper section rods are formed substantially hook-shaped, as at 21, so that they may act as coat or hat-hangers when desired.

100 An umbrella clip 22, may be provided on the lower section 1, with a drawer 23 underneath to catch the drip from the umbrella held thereby.

105 Having thus indicated the various parts of my invention I will now describe briefly its operation.

The device when closed is as shown in Fig. 1, and it may be used then in a limited fashion or it may be used when partly extended but when its maximum capacity is required it is extended to its full height, as shown in Fig. 1, when all the drying rods may then be utilized, and in order to bring the rods from their normal vertical position to the horizontal position all that is necessary is to grasp the knob on the end of one rod of a group and raise it as far as it will come thus raising simultaneously all the rods in that group, when they may be allowed to fall over to the horizontal position, being then supported horizontally by the bearing each rod has on the covering plates 6, 11 or 15, as the case may be.

The various groups of rods are returned to their normal positions within their respective compartments by raising one member of a group from the horizontal and pressing down on the plate 19 of that group, the descending plate drawing all the rods connected to it down until they assume the vertical position, as shown in Fig. 4.

It will be seen, therefore, that I have devised a simple, compact, and convenient clothes drier, having a maximum clothes-drying capacity considering its adaptability to places of limited accommodation, and in which the clothes-supporting rods are adjusted quickly and with great facility.

What I claim as my invention is:—

1. A clothes drier comprising a suitably supported column having inner and outer casings connected together by a closure member at their upper ends, the space between said casings being subdivided by vertical partitions and the said closure being provided

with a plurality of spaced openings, a plurality of withdrawable arms arranged in groups to hang within the subdivisions, the upper ends of said arms being extended through said openings and provided with enlargements normally resting on the closure member, and plate members vertically movable in each subdivision to which each member of the respective group therein is flexibly connected.

2. A clothes drier comprising a suitably supported lower column having inner and outer casings connected together by a closure member at their upper ends, the said closure being provided with a plurality of spaced openings, an intermediate column vertically adjustable in the said inner casing and also consisting of inner and outer casings connected together by an upper closure member having a plurality of spaced openings, an upper column vertically adjustable in the inner casing of the intermediate column closed at its upper end and having a plurality of spaced openings in the closure, a plurality of withdrawable arms normally arranged to hang within each column having their upper ends extended through said openings and enlarged so as to be supported from the respective closure members, means on the lower ends of said arms for preventing their disengagement from their respective columns when withdrawn to assume a horizontal position, and means for securing the intermediate and upper columns in any vertically adjusted position.

Dated at Vancouver, B. C., this 16th day of February, 1918.

EDWARD WIDEEN.
